provided such changes fall within the purview of what is claimed.

I claim:

1. A combined envelope opener, paper cutter and punch, comprising a frame, a slidably mounted shaft carried by the frame, means for actuating the shaft to force an end of the shaft through a sheet or sheets of material to form a punched hole therein, a rotary cutter carried on the other end of the shaft, a second rotary cutter cooperating with the first cutter to open an envelope passed therebetween, the position of the first cutter with respect to the second being determinable by the position of the shaft, and an adjustable guide for regulating the point at which an envelope or sheet of material is cut.

the interests of science and, in this, a very large
amount of time & effort will be spent and will result
in great benefit to the community. It is necessary that
these studies be carried out in a systematic & scientific way, so as to obtain
the best possible results. The best way to do this
will be to have a committee of experts, who will be
able to study the problem in all its aspects, and to
make recommendations to the appropriate authorities
about what should be done. This will be a
great service to the community, and will help to
ensure that the results of the study will be
of great benefit to all.

means for sliding the shaft, means for tensioning the shaft and returning it to a normal position of rest, a guide for determining the position of the cut, and a keeper having a guard formed with an opening, the free end of the slideable shaft operating against the guard to form a punch.

3. A cutting and punching device, comprising a slideable shaft functioning as a punch, a rotary cutter on the opposite end of the shaft, means 10 for actuating the shaft comprising an arm pivotally mounted on said frame and pivotally connected to said shaft and an operating lever, which is pivotally connected to said frame, a spring connected to said lever to retain said actuated means 15 in inoperative position, a fixed rotary cutter co-operating with said first rotary cutter, and said first rotary cutter being movable with respect to the fixed cutter upon movement of the shaft to adjust the proximity of the cutters to perform 20 a clean sharp cut.

HARRY L. McDANIEL.

the first time, and the first time that the
whole of the population of the country
had been called together for the purpose
of a national assembly. The first
meeting of the assembly was held on the
14th of June, 1789, in the hall of the
Tuilleries, and the members were
selected by the electors of each
district. The assembly was composed
of 828 members, and the first
order of business was to consider
the question of the abolition of
the existing system of taxation.
